UNITED STATES PATENT OFFICE.

ORIS H. NICKERSON, OF CLEVELAND, OHIO.

DESIGN FOR A RECEPTACLE.

52,805.

Specification for Design.

Patented Dec. 24, 1918.

Application filed April 23, 1917. Serial No. 164,070. Term of patent 14 years.

To all whom it may concern:

Be it known that I, ORIS H. NICKERSON, a citizen of the United States, residing at Cleveland, in the county of Cuyahoga and State of Ohio, have invented a new, original, and ornamental Design for Receptacles, of which the following is a specification, reference being had to the accompanying drawing, forming part hereof, wherein—

Figure 1 is a perspective view, Fig. 2 a

front elevation, and Fig. 3 a side elevation of the receptacle exhibiting my new design.

Receptacles of this nature are used for housing electrical switches, sockets, and the like, and are commonly known as "switch-boxes".

I claim:—

The ornamental design for a receptacle as shown.

ORIS H. NICKERSON.
